INDEX TAB FOR GUIDE CARDS

Robert S. Daniel, Alexandria, Va., and Maxwell S. Fulcher, Washington, D. C.

Application March 21, 1950, Serial No. 150,958

1 Claim. (Cl. 129—16.8)

2

The present invention relates to improvements in means designed to facilitate the filing, location and removal of office papers or the like in or from the drawers of file cabinets or other similar file repositories.

More particularly, the present invention is concerned with improved means for holding and/or dividing card files or folders that stand on edge in a drawer or the like, such means carrying readily visible tabs or the like for purposes of classification of the stored material.

An object of the present invention is to provide an index or classification tab that is slidable along the top of a partition and yet easily removable and replaceable without removal of the partition.

Another object of the present invention is the provision of a new and improved resilient clip device for mounting the tab upon the partition.

A still further object of the present invention resides in the provision of a novel and simple connection between a slideable file supporting and/or dividing member and a rod that is mounted longitudinally of the base of a cabinet drawer or the like, having means on the slideable member for frictionally holding it in adjusted position when it is slightly tilted.

A still further object of the present invention is the provision of means adjacent the longitudinal edge of a file dividing device for engagement with a tab.

Another object of the present invention is the provision of a tab slideable along the top of a file dividing device and having means for locking engagement with means adjacent the longitudinal edge of said file dividing device.

A still further object of the present invention is to provide new and improved file supporting and dividing members and index tabs, per se, as well as a novel and useful interconnection between said members and said tabs.

The foregoing and other objects of the present invention should clearly appear from the following detailed description when studied in conjunction with the accompanying drawing, wherein:

Figure 1 is a front elevational view of the filing device and showing the adjustable tab and the slotted tongue.

Figure 2 is a side elevational view taken on line 2—2 of Figure 1 and looking in the direction of the arrows, the broken line representing a tilted position;

Figure 3 is a top plan view of the base portion taken on line 3—3 looking in the direction of the arrows and showing the slot in the base;

Figure 4 is an enlarged sectional view taken on line 4—4 of Figure 1, a part being shown fragmentarily;

Figure 5 is a rear elevational view of the adjustable tab; and

Figure 6 is a partial fragmentary front view showing the device tilted back until the slot grips the guide rod.

Referring to the drawing the numeral 7 designates an L-shaped dividing and supporting member in its entirety, designed for use in a pull-out cabinet drawer or its equivalent. The member 7 comprises a vertical plate 8 integrally joined to a horizontal base plate 9, the latter having a central elongated aperture 10 produced by striking out a pair of supporting feet 12 and 13 therefrom in spaced relationship.

The feet 12 and 13 have apertures 14 therein to connect them for free travel along a cylindrical rod 15 that conventionally forms a front-to-back element of many types of file cabinet drawers now in use. The paper ends of the apertures 14 are of semi-circular configuration and of a greater diameter than the diameter of the rod 15 so as to slide freely when pushed or pulled horizontally, but the lower ends of one or both, and especially, that of the foot 12 are tapered downwardly to a width slightly less than the rod diameter so that by tilting the member 7 slightly in a rearward direction it may be frictionally secured to the rod in any position of sliding adjustment. The tilted position is illustrated in broken lines in Figure 2, and in Figure 6, and in this view the L-shaped dividing member is shown fragmentarily. Hence this simple interconnection permits a plurality of cards or other papers that stand on edge upon the platform 9 to be loosened, viewed and repacked with ease and without the need of spring clamps or other extraneous devices that until now have been utilized to hold a slideable partition in adjusted position. As shown in Figure 6 when the L-shaped element is tilted rearwardly the tapering side walls grip the rod 15.

Adjacent the longitudinal edge of the plate 8 a plurality of equally spaced and horizontally aligned dimples 16 is provided, and they are preferably circular, in the form of protuberances pressed or stamped therefrom. A tab 17 in the form of a clip is slipped onto the edge of the panel 8 for cooperation with the dimples 16. This tab is slideable along the upper edge of the panel and also is readily removable and replaceable vertically of the panel.

55 The tab member 17 comprises a pair of inter-

grally joined, substantially parallel walls 18 and 19 designed to straddle the panel 8 and having a plurality (at least two) of dimples 20 and 22, respectively, complementary to the dimples 16 and spaced equally in alignment. The detents 20 receive the convex sides of the dimples 16, and the detents 22 frictionally slide into the concave sides of the dimples 16. To prevent distortional spreading of the clip wall 18 there is provided a pair of integral fingers 23 cut therefrom and bent backwardly around the lateral edges of the wall 19. In addition to holding the walls in properly spaced relationship these fingers also serve, (1) to strike the top edge of the panel 8 and thus properly position the tab when it is pressed downwardly onto the panel, and (2) as a support for an index or name card to be inserted in the U-shaped opening 24 at the top of the tab. If desired the fingers 23 may be eliminated and the edges welded together.

The opening 24 is faced by a window 25 through which an indexed card (not shown) may be viewed. Also, preferably, the wall 19 has an opposite, smaller window 26, the two windows affording openings through which portions of the thumb and forefinger may be inserted to facilitate insertion and removal of the index card.

The method of use of our improved device should now be fairly obvious. The tab 17 is readily clipped onto the upper edge of the panel 8 and slideable longitudinally thereof into frictionally fixed positions corresponding in number to the dimples 16. The entire member 7 and its associated tab can be moved forwardly and rearwardly to tighten or loosen a bundle of material for convenient inspection, and frictionally locked in place by tilting the member 7 rearwardly.

It will be understood that the above description and the accompanying drawing comprehends only the general and preferred embodiment of our invention, and that various minor changes in details of construction may be made without de-

parting from the scope of the invention and the claim hereto appended.

What is claimed is:

5 A guide card for indexing the contents of a file comprising a substantially rectangular plate having a row of longitudinally spaced dimples adjacent one edge thereof, an index tab embracing the edge of the plate adjacent the row of dimples, said index tab comprising a substantially U-shaped clip having opposite legs engaging opposite faces of the plate adjacent the row of dimples therein, and dimples in opposite legs of the clip for engaging opposite sides of the dimples in the plate and holding the tab in adjusted position on the plate, and fingers carried by opposite side edges of one leg of the U-shaped clip intermediate the ends thereof, said fingers extending around opposite side edges of the opposite leg of the U-shaped clip to form stops for engaging the adjacent edge of the plate and aligning the dimples carried by the clip with those carried by the plate and to define with the bight portion and the legs of the U-shaped clip an index card receiving chamber.
